UNITED STATES PATENT OFFICE.

CHRISTIAN VON HOFF, OF WILMERSDORF, NEAR BERLIN, GERMANY, ASSIGNOR TO THE FIRM OF OPTISCHE ANSTALT C. P. GOERZ AKTIENGESELLSCHAFT, OF FRIEDENAU, NEAR BERLIN, GERMANY.

ANGULAR MIRROR.

1,027,420.

Specification of Letters Patent.

Patented May 28, 1912.

Application filed October 12, 1911. Serial No. 654,357.

To all whom it may concern:

Be it known that I, CHRISTIAN VON HOFF, a citizen of the German Empire, and resident of Wilmersdorf, near Berlin, Germany, 5 have invented certain new and useful Improvements in Angular Mirrors, of which the following is a specification.

This invention relates to angular mirrors and its object is to provide a construction 10 whereby invariability of the angle inclosed by the mirror surfaces is insured. According to the invention this object is attained in forming the angular mirror body of a separate support with reflectors attached thereto, and in using for the support a material whereof the thermic expansion coefficient is approximately zero, with reflectors 15 of a different coefficient of expansion arranged thereon in such manner that they can move relatively to the support, parallel 20 with their reflective surfaces. In this manner the angle inclosed by the reflectors is kept perfectly constant by means of the non-expanding support, without occurrence of 25 strains in the reflectors, due to the difference in the coefficients of expansion. As material for the reflector support nickel-steel alloy is suitable, containing about 36.1% of nickel. A convenient and cheap form of support is 30 obtained by using a yoke of nickel-steel, with its limbs adjusted so that their lateral edges inclose the angle which is to be the angle of the mirror.

The connection of the support to the reflectors is with advantage made by making the reflectors abut against the support at three points, and pressing them against the support at these points.

One form of construction of the improved 40 angular mirror is shown in the accompanying drawing, in which—

Figure 1 shows the angular mirror in cross section; Fig. 2 shows the same in side view, and Fig. 3 shows the nickel-steel blank 45 out of which the yoke shaped support for the reflectors is made.

The two lateral limbs of the yoke-shaped support for the reflectors are marked 1. These limbs are connected by a bridge 2. 50 The lateral edges 3 of the limbs inclose the

angle which the mirror is to have. Each reflector 4 rests at three points 5 on the support. A three armed spring 6 serves to press each reflector against the support at the abutment points 5. The springs 6 are 55 acted on by springs 7, which are fixed at 8 to the bridge connecting the limbs 1. Pins 9 on the limbs project into recesses 10 in the reflectors and limit in a suitable degree the freedom of movement of the reflectors on 60 the support.

The new angular mirror is designed for use in telescopic instruments such as base line telemeters where it is essential that the rays entering the instrument are deviated 65 by reflecting devices through definite angles which remain unaltered independently from variations of temperature which the instrument may undergo.

What I claim is:

1. An angular mirror, comprising a support, consisting of a material whereof the thermic expansion coefficient is approximately zero, and reflectors of different expansion coefficient mounted on said support 75 in such manner that they can move relatively to the support, parallel with their reflecting surfaces.

2. An angular mirror, comprising a yoke-shaped reflector support of nickel-steel alloy 80 whereof the limbs are adjusted so that their lateral edges inclose the angle required for the angular mirror, and reflectors mounted on the lateral edges of said yoke limbs in such a manner that they can move relatively to 85 their support parallel with their reflecting surfaces.

3. An angular mirror, comprising a support, consisting of a material whereof the thermic expansion coefficient is approximately 90 zero, reflectors mounted thereon, three abutment points on said support for each reflector and pressure exerting means adapted to press the reflectors against the abutment points, the reflectors being free 95 to move relatively to their support parallel with their reflecting surfaces.

4. An angular mirror, comprising a support, consisting of a material whereof the thermic expansion coefficient is approxi- 100

mately zero, reflectors mounted thereon, three abutment points on said support for each reflector and springs mounted on the reflector support adapted to press the reflectors against their abutment points, said pressure springs having their contacting points in line with the abutment points.

In testimony whereof I have signed this specification in the presence of two subscribing witnesses.

CHRISTIAN VON HOFE.
